UNITED STATES PATENT OFFICE

163,075

REFRIGERATOR

Clifford Brooks Stevens, Fox Point, and John Hughes, Jr., Whitefish Bay, Wis., assignors to Gibson Refrigerator Company, Greenville, Mich., a corporation of Michigan

Application November 21, 1950, Serial No. 13,082

Term of patent 14 years

(Cl. D67—2)

To all whom it may concern:

Be it known that we, Clifford Brooks Stevens, a citizen of the United States, residing at Fox Point, county of Milwaukee, and State of Wisconsin, and John Hughes, Jr., a citizen of the United States, residing at Whitefish Bay, county of Milwaukee, and State of Wisconsin, have invented a new, original, and ornamental Design for a Refrigerator, of which the following is a specification, reference being had to the accompanying drawing, forming a part thereof, in which:

We claim:

The ornamental design for a refrigerator, as shown.

CLIFFORD BROOKS STEVENS.
JOHN HUGHES, Jr.
